UNITED STATES PATENT OFFICE.

ALBERT H. STEBBINS, OF LOS ANGELES, CALIFORNIA.

FRAME SUPPORTING AND OPERATING MECHANISM.

Application filed April 30, 1926. Serial No. 105,886.

This invention relates to means for supporting a frame for vibratory movement, and also to means for moving the frame back and forth to vibrate the same.

Concentrator decks and screens are frequently supported for vibratory movement by pivoted arms through which the deck or screen frame is suspended from a supporting structure. This type of supporting means is employed because as the pivoted arms rock through the arc of a circle they impart an up-throw movement to the frame they support, and this up-throw movement is desirable because it promotes the travel of the materials being treated along the material supporting surface. The bearings or pivot points of these rocking arms, however, tend to wear out rapidly, due largely to the presence of dirt and dust about the machines, and they require frequent lubrication.

One of the features of the present invention therefore resides in a novel cable construction for suspending a deck, screen or other frame to be vibrated so that as the frame is moved back and forth the cables impart a rising and falling or up-throw movement to the frame. These supporting cables have the advantage that they do not need to be lubricated, and they are not injured by the dirt and dust that may lodge on the cables and their bearing surfaces.

Another feature of the invention resides in the arrangement whereby the frame supporting cables are caused to wind upon and unwind from bearing blocks as the frame they support is moved back and forth, and as a result of this construction a greater up-throw movement may be imparted to the frame than can be secured through the use of the rocking arms employed heretofore.

The use of cables for supporting a vibratory frame for back and forth movement in accordance with the present invention has the further advantage, in that the active length of each supporting cable may be readily varied to cause the same to properly support the portion of the frame to which it is connected.

Still another feature of the invention resides in the construction whereby a cable is employed to move the frame back and forth, and in the connections between the frame and operating cable whereby the frame is relieved from the tensioning pull to which the cable is subjected. In ac-

cordance with the present invention the pull of the operating cable is transmitted to the frame by two or more clamps that are secured to the frame at spaced points lengthwise of the same, and one of the clamps is constructed to grip the cable firmly so that it cannot slip through the clamp, while the other clamps frictionally engage the cable so that they impart the movement of the cable to the frame but at the same time permit any slack in the cable to be drawn through the clamps. As a result of this construction the frame is relieved from the tensioning pull to which the operating cable is subjected.

The foregoing features of the present invention may be employed to support and vibrate a concentrator deck or screen, but they are particularly well adapted to support and operate relatively long conveyors, because the up-throw movement developed by the frame supporting cables helps to advance the materials along the conveyor, while the connections between the operating cable and conveyor will relieve the latter from excessive strains.

Other features of the invention and novel combination of parts in addition to the above will be hereinafter described in connection with the accompanying drawings, which illustrate good practical forms of the invention.

In the drawings—

Fig. 1 is a side elevation of a vibratory conveyor having associated therewith the features of the present invention.

Fig. 2 is an end view looking at the right-hand end of the conveyor of Fig. 1;

Fig. 3 on an enlarged scale is a side view of that portion of the conveyor of Fig. 1 which is provided with the tight clamp adjacent the left-hand end of the conveyor.

Fig. 4 on an enlarged scale is a side view of the base plate of the clamp shown in Fig. 3, the cover plate being omitted;

Fig. 5 is an end view of Fig. 4, but shows the cover plate in place;

Fig. 6 on an enlarged scale is a perspective view looking at the right-hand end of the conveyor of Fig. 1;

Fig. 7 is a side view of a modified arrangement of one of the cable supports, and shows one of the semi-tight cable clamps; and

Fig. 8 is an end view of parts shown in Fig. 7.

The novel features forming the subject

matter of the present invention have been shown in the drawings as associated with a vibratory conveyor for advancing materials lengthwise of the same; it will be understood, however, that the features of the present invention are well adapted for use in connection with concentrator decks, screens, frames and other devices which employ a vibratory movement.

10 The frame supporting structure from which the frame or conveyor is suspended may be formed in various ways and is shown in the drawings as comprising a cage formed of the spaced lower channel irons 10 to which the uprights 11 are secured, and the upper ends of these uprights are fastened to horizontally extending rails 12. This entire cage is rigidly secured to the vertically disposed beams 13, and the inclined braces 14 are provided which extend downwardly from the beams 13 to the outer rails 12, as will be apparent from Fig. 6.

15 The conveyor which is suspended within this hollow cage may have the form of a trough, and is conveniently formed of sheet metal having the bottom or floor 15 and the side walls 16, and this sheet metal trough may be strengthened by securing thereto the side rails 17 to which the uprights 18 are fastened.

20 It is assumed that the conveyor is operated to advance the materials lengthwise of the same toward its right-hand end, as indicated by the arrow shown in Fig. 1. The means for supporting the conveyor is therefore constructed to cooperate with the movement imparted to the frame so that this combined action will promote the travel of the materials along the conveyor in the direction indicated by the arrow.

25 As stated, one of the features of the present invention resides in the means for supporting the conveyor or frame for back and forth or vibratory movement, and to this end the conveyor trough 15 is supported at any desired number of points by the cables, straps, or chains 19. The supporting elements 19 are shown and described as consisting of cables, but it will be understood 30 that other flexible supporting means such as straps and chains may be employed in place of the cable. The term "cable" as used in the claims to designate the elements 19 should therefore be construed as covering not only cables, but equivalent flexible elements.

35 In accordance with the present invention the lower end of each of the cables 19 is bent around a curved bearing block 20, which preferably has a cable receiving groove formed in its lower face. These bearing blocks are rigidly secured to the side plates 18 of the conveyor trough by bolts 21, and one end of each of the cables 19 is firmly secured to the bearing block 20 40 by a clamp 22. Each cable 19 extends up-

wardly from its bearing block 20 to a bearing block 23 which is rigidly secured to a side rail 12 of the supporting cage. The bearing blocks 23, like the bearing blocks 20, are provided with cable receiving grooves, 45 and it is desirable that means be provided for adjusting the effective length of each of the supporting cables 19. To this end, in the construction shown, each bearing block 23 is provided with an upwardly extending lug 50 through which a hole is formed, and in this hole is mounted a threaded pipe 25 which is leaded or otherwise secured to the upper end of the cable 19. The nuts 26 having threaded engagement with the pipes 55 25 may be adjusted as desired to vary the effective length of the cables 19.

60 The arrangement of the bearing blocks 20 and 23 as shown in Figs. 1, 2, 3, and 6 is such that as the trough or conveyor 15 is moved in a right-hand direction the lower portion of the cable 19 will wrap about its bearing block 20, while the upper portion of the cable 19 will likewise wrap about its bearing block 23. As a result of the wrapping of the cable 19 about both of the bearing blocks as the trough 15 moves in a right-hand direction, and an unwrapping of the cable 19 from both of its bearing blocks as the trough moves in a left-hand direction, the supporting cables will impart a pronounced rising and falling movement to the trough 15 as it moves back and forth through a path of travel lying to the right hand side of the vertical position in which the cable 19 is shown. That is, if the means which will presently be described for vibrating the trough 15, is adjusted so that the path of movement through which the trough is vibrated lies entirely or nearly entirely to the 65 right of the vertical position in which the cables 19 are shown, then the wrapping effect of these cables will impart a pronounced rising or up-throw movement to the trough 15. This up-thrown movement, which is most pronounced at the end of the stroke in a right-hand direction, is desirable because it imparts a tossing movement to the materials which promotes their travel lengthwise of the trough in the direction indicated by the 70 arrow in Fig. 1.

75 The arrangement of the supporting cables 19 just described is desirable if a pronounced upthrow movement is to be imparted to the conveyor or other device as it approaches the end of its stroke in a right-hand direction, but in some devices it may be desirable to employ the supporting cables 19 without imparting a substantial up-throw movement to the conveyor or the like. In such case the position of the blocks 20 and 23 about which the cables wind may be reversed as shown in Fig. 7, wherein it will be noted that the blocks are arranged so that as the trough 15 is moved in a right-hand direction 80

the cable 19 will unwrap from both the lower block 20 and the upper block 23, and will wrap about both of these blocks as the trough moves in a left-hand direction. As a result 5 of this modified arrangement of Fig. 7 the rising movement imparted to the conveyor 15 as it moves in a right-hand direction will be much less than that produced by the cable-supporting structure of Figs. 1 and 3.

10 As above stated the present invention relates not only to novel means for supporting a conveyor or frame for vibratory movement, but is directed also to novel means for moving the frame back and forth in the direction of its length, and the means shown to this end will now be described. In order to cause the materials to travel lengthwise of the trough or supporting frame, the material supporting surface must be held at a 15 substantially downward slope in the direction in which the materials are to travel, or a pronounced progressive vibratory movement must be imparted to the material supporting surface to advance the materials 20 along this surface. The vibratory movement commonly imparted to a vibratory frame may be of such strength that it places a pronounced strain upon the frame which is being vibrated, and in order to relieve the 25 material supporting frame from this strain the present invention contemplates an arrangement whereby one or more operating cables 27 are provided. These cables extend lengthwise of the conveyor or frame, and they are preferably secured to the frame to be vibrated at a plurality of points lengthwise of the frame, the arrangement being such that the tensional pull exerted upon the operating cables 27 to move them back and 30 forth is not imparted to the vibratory frame.

In the construction shown two operating cables 27 are provided, one being disposed at each side of the conveyor or trough 15. Each of these cables is rigidly secured to the 35 trough 15 at a point near the left-hand end of the trough by the cable gripping clamp 28 which is formed of a base plate 29 and a cap plate 30, and these two plates are secured to the portion 18 of the trough by the clamping bolts 31. The construction of the clamp 28 is such that the cable 27 can not slip therethrough and the clamp is therefore provided with a serpentine groove which is formed so that a pronounced bend will be 45 imparted to the cable lying in this groove, as will be apparent from Fig. 4, wherein it will be seen that the cable is bent around the side lugs 32 and an intermediate lug 33. The plates 29 and 30, which may be similar in 50 construction, are held in clamping engagement with the cable 27 by the bolts 31 which pass through the bolt holes 34.

It is apparent that if each of the operating cables 27 should be secured to the trough 15

by several clamps each having the construction of the clamp 28, the cable would not be permitted to slip through these clamps, even if slack should occur in the cable between the spaced clamps. Under this condition a pronounced pull upon the cable 27 would exert 65 an excessive displacing pull upon the clamps. To avoid this condition the present invention contemplates a construction whereby each cable 27 is rigidly connected to the trough 15 at additional points by the semi-tight clamps 35 which, it will be noted, differ in construction from the clamp 28 in that they impart only a slight bend to the portion 70 of the cable which is gripped between the base plate 36 and cap plate 37. The construction of the clamps 35 should be such that they will grip the operating cables 27 with sufficient friction to impart the movement of the cable to the portion of the trough 15 to which they are secured, while at the same time they will permit any slack 75 which may occur in the cables to be drawn 80 through the semi-tight clamps 35. 85

As a result of this construction the pull exerted upon the cables 27 to move the same back and forth is imparted to the conveyor 15, while at the same time the conveyor is relieved from the strong tensional pull to 90 which the cables are subjected. From the foregoing it will be seen that the construction of the supporting cables 19 and the operating cables 27 is such that they relieve 95 the trough 15 from excessive strain, and as 100 a result permit a reduction in weight and in the strength of the conveyor 15 or other frame which is operated in accordance with the present invention.

The means employed for pulling the cables 105 27 back and forth might be variously constructed, and in the arrangement shown in the drawings the right-hand end of each cable 27 passes downwardly about a grooved sheave 38 which is supported by the transversely extending shaft 39 the ends of which are supported by bearing brackets 40 secured to the channel irons 10, and the downwardly extending end of each of these cables is secured to a coiled spring 41. A nut 42 110 mounted upon the pipe or bolt 43 secured to the lower end of the cable may be adjusted to vary the tension of the spring 41 to thereby vary the pull which this spring exerts 115 upon the cable to move the trough 15 in a 120 right-hand direction.

The means shown for pulling the cables 125 27 in a left-hand direction consists of the power shaft 44 which may be driven by the usual pulley not shown, and upon this shaft is mounted a pair of eccentrics 45, one being provided for each of the cables 27. These eccentrics rotate within grooved sheaves 46

mounted upon the eccentrics. The left-hand end of each of the cables 27 is shown as anchored to the fixed cage by an adjustable bolt 47, and a portion of each cable is looped 5 about the grooved sheave 46, as clearly shown in Fig. 1. Each cable extends from this grooved sheave to the idle sheave 48 which is rotatably supported near the left-hand end of the cage. The power operating means 10 just described for pulling the cables 27 in a right-hand direction is desirable because by looping each cable about its operating eccentric 45 as shown, the movement imparted to the cable will be equal to twice 15 the throw of the eccentric 45, thus permitting the use of an eccentric which is offset only a slight amount from its operating shaft. It will be understood that the tension of the spring 41 should be such that it 20 will impart a pull to the trough 15 which is quicker or more energetic than the pull which is imparted to this trough in a left-hand direction by the power operating eccentric. This is necessary in order to advance 25 the materials lengthwise of the trough in the direction indicated by the arrow. It will be understood, however, that travel of the materials lengthwise of the trough in a right-hand direction is assisted by the up- 30 throw movement which is given to the trough by the suspension cables 19.

What is claimed is:—

1. In combination with a frame supporting structure, a frame supported by said 35 structure for vibratory movement in the direction of its length, means for vibrating the frame, comprising a cable extending lengthwise of the frame, means for pulling the cable back and forth, a tight clamp secured to the frame and constructed to grip 40 the cable so that it will not slip within the clamp, and a semi-tight clamp secured to the frame in spaced relation to the tight clamp and constructed to grip the cable with sufficient 45 friction to impart the pull of the cable to the frame while permitting the cable to be pulled through the clamp to take up slack.

2. In combination with a frame supporting structure, a frame supported by said 50 structure for vibratory movement, means for vibrating the frame, comprising a cable extending lengthwise of the frame, means for pulling the cable back and forth, and means for imparting the movement of the cable to the frame including a tight clamp secured to the frame and adapted to firmly 55 grip the cable, and a semi-tight clamp secured to the frame and adapted to frictionally grip the cable to impart movement 60 of the cable to the frame without preventing the slack in the cable from being drawn through the semi-tight clamp.

3. In combination with a frame supporting structure, a frame supported by said 65 structure for vibratory movement, means for

vibrating the frame, comprising a cable extending lengthwise of the frame, means for pulling the cable back and forth, and means for imparting the movement of the cable to the frame, including a plurality of cable 70 engaging clamps disposed lengthwise of the frame, one of said clamps being constructed to grip the cable so that it cannot slip therethrough and the other clamps being constructed to grip the cable with sufficient 75 friction to impart the pull of the cable to the clamp while permitting the slack in the cable to be drawn through these clamps.

4. In combination with a frame supporting structure, a frame supported by said 80 structure for vibratory movement, means for vibrating the frame comprising cables extending lengthwise of the frame at the opposite sides thereof, means for pulling the cables back and forth, and means for imparting the movement of the cables to the frame, including a plurality of cable engaging clamps disposed lengthwise of the frame, one clamp for each cable being constructed to positively grip the cable so that it will 85 not slip through the clamp and the other clamp being constructed to grip the cable with sufficient friction to impart the pull of the cable to the clamp while permitting the slack in the cable to be drawn through the 90 clamp.

5. In combination with a frame supporting structure, a frame supported by said structure for vibratory movement, means for vibrating the frame, comprising a cable extending lengthwise of the frame, means for pulling the cable back and forth, and clamps for connecting the frame to the cable at a multiplicity of points throughout the length of the frame and constructed to frictionally 100 engage the cable to impart the movement of the cable to the frame without subjecting the frame to the tensioning pull to which the cable is subjected.

6. In combination with a frame supporting structure, a frame supported by said structure for vibratory movement, means for vibrating the frame, comprising a cable extending lengthwise of the frame, clamps for connecting the frame to the cable at a plurality of points lengthwise of the frame and constructed to frictionally engage the cable to impart the movement of the cable to the frame without subjecting the frame to the tensioning pull to which the cable is 110 subjected, a spring for pulling the cable in one direction, and power actuated means for pulling the cable in the opposite direction.

7. In combination with a frame supporting structure, a vibratory frame, cables for supporting the frame suspended from the supporting structure, rounded bearing blocks secured to the frame and supporting structure and each block having a cable receiving groove formed in its curved face, an- 125 130

choring means for holding one end of each cable bent about a frame bearing block, anchoring means for holding the other end of each cable bent about a supporting structure bearing block, and one of the anchoring means for each cable being adjustable to pull the cable in the direction of its length

around its adjacent bearing block to thereby vary the effective length of the frame supporting cable.

10

In testimony whereof, I have signed my name to this specification.

ALBERT H. STEBBINS.
